UNITED STATES PATENT OFFICE.

JAMES F. COLBY, OF BUFFALO, NEW YORK.

SLEEPING-CAR.

SPECIFICATION forming part of Letters Patent No. 313,576, dated March 10, 1885.

Application filed March 20, 1884. (No model.)

To all whom it may concern:

Be it known that I, JAMES F. COLBY, a citizen of the United States, residing at Buffalo, in the county of Erie and State of New York, 5 have invented certain new and useful Improvements in Sleeping-Cars, of which the following is a specification, reference being had therein to the accompanying drawings.

This invention relates to certain new and 10 useful improvements in sleeping-cars; and it has for its objects, first, to provide such an arrangement of seats in a railway-car that they may be made of sufficient length to enable passengers to lie down at full length on 15 them; second, to provide such an arrangement of transverse seats in a railway-car that one set will occupy one side of one-half of the car, and the other set will occupy the other side of the other half of the car, thus effecting 20 an equal distribution of the weight; third, to provide, in addition to the transverse seats in the car, seats running in a longitudinal direction, which are also of sufficient length to enable a passenger to lie down at full length, and 25 arranged relatively in the same manner as the transverse seats; and, fourth, to provide a support for the seat, a portion of which will also serve the purpose of a head-rest.

In the accompanying drawings, forming a 30 part of this specification, and on which the same letters of reference indicate the same or corresponding features, Figure 1 represents a plan view of the flooring of a railway-car, showing my improved manner of arranging 35 the seats; Fig. 2, a cross-sectional view of a portion of the car, showing one of the transverse seats in front elevation and one of the longitudinal seats in end elevation; Fig. 3, a plan view of the seat-frame with the upholstering removed; Fig. 4, a detail perspective view of the support and head-rest, and Fig. 40 5 a modified form of the head-rest.

The letter A designates a car-flooring, which 45 may be of the ordinary or any approved construction, on which I mount two sets of transverse seats and two sets of longitudinal seats. The former of these seats are placed so that one set will occupy one side of one-half of the car, and the other set will occupy the other 50 side of the other half of the car. The object

of this arrangement is to afford room for seats of such length as to enable persons to lie down upon them at full length, and also to effect an equal division of the weight on either side of the car. The longitudinal sets of seats are 55 arranged relatively with the other in the same manner as the transverse seats are relatively arranged. The several seats of each set in the longitudinal series are contiguous one to the other. The transverse seats are 60 constructed of a frame, B, of metal or of wood, and provided with a series of apertures. Secured to these apertures are a series of transverse curled or spiral wire springs, which collectively form a support for the mattress or 65 cushion, to be presently described.

The letter C refers to the end pieces of the 70 respective seats, the same being preferably constructed of cast-iron. The lower portions of these pieces constitute the supporting-legs 75 for one end of the seats, and the upper portions of these pieces constitute head-rests. The portions forming head-rests are curved upwardly, so as to bring them in a plane above the seat proper, as indicated, so as to form a 80 convenient and comfortable support for the head, and to practically lengthen the seats by reason of their overhang. They are provided with a series of apertures, to which are connected the springs, as above described in reference to the frame proper of the seats. This piece C is further provided, at the upper end 85 of the part which constitutes the supporting-legs, with an offset adapted to receive and sustain the adjacent end of the frame B. The 90 opposite end of this frame is supported by a leg, D, the upper portion of which terminates in an arm of any approved configuration. These seats are provided with the usual backs, E, the arms by which they are pivotally connected with the seat being in this instance attached to a convenient part of the head-rest and to the seat-arm.

The letter F refers to the longitudinal seats, 95 the frames of which are constructed in the manner above described. The head-rests are also constructed in the same manner, save that in this instance they are provided with lugs H instead of with the offset, whereby the supports for the frames are provided.

As represented in Figs. 1 and 5, it will be observed that the head-rest of each horizontal seat overhangs the foot end of the next succeeding seat, thereby economizing in space 5 and utilizing all the available room in a car.

The lower portions of the pieces which constitute the head-rest also form, as above described, supporting-legs for the longitudinal seats. These legs may be of any desired configuration, so as to be secured to the flooring or to the sides of the car, as represented in Fig. 2. The cushions, which are fitted upon the seats, are supported by the springs secured to the frame of the seat and to the head-rest, 15 and are of such configuration as to evenly and smoothly cover the same.

It will be observed that by reason of the above arrangement the seats cannot only be made long enough to accommodate a person 20 in a lying posture, and the weight equally distributed over the car, but that ample room is left to form a proper passage-way or aisle. This arrangement practically affords the same facilities for rest and sleep at night in a passenger-car of the ordinary type as is afforded 25 by a sleeping-car.

Having thus fully described my invention, what I claim as new, and desire to secure by Letters Patent, is—

30 1. In a railway-car, the sets of transverse seats arranged so that one set will occupy more than one-half the width of one portion of the car, and the other set will occupy more than one-half the width of the other portion of the car, and the sets of longitudinal seats arranged 35 each to occupy the portion of the car opposite the respective transverse seats.

2. In a railway-car, the combination, with the sets of transverse seats so arranged that 40 one set will occupy more than one-half of the width of one portion of the car, and the other set will occupy more than one-half the width

of the other portion of the car, the respective seats of each set being provided with overhanging upwardly-curved head-rests, of the 45 sets of longitudinal seats, the seats of the respective sets being contiguous one to the other, and each provided with upwardly-curved overhanging head-rests, and each set arranged to occupy the portions of the car opposite the 50 respective sets of transverse seats.

3. In a railway-car, the sets of longitudinal seats arranged so that one set will occupy one side of one portion of the car, and the other set the other side of the other portion of the 55 car, the seats of the respective sets being contiguous one to the other, and each provided with an upwardly-curved overhanging head-rest.

4. In a railway-car seat, the combination, 60 with the frame proper, of the combined head-rest and supporting-legs constructed of one piece.

5. In a railway-car seat, the combination, 65 with the frame proper, having a series of transverse springs secured thereto, of the combined head-rest and supporting-legs, having an offset to which the frame is secured, and a series of transverse springs secured thereto.

6. In a railway-car seat, the combination of 70 the seat proper with the upwardly-curved overhanging head-rest, forming an elongation of the seat.

7. In a car-seat, the combined head-rest and supporting-legs constructed of one piece, and 75 having a part adapted to receive and sustain the seat.

In testimony whereof I affix my signature in presence of two witnesses.

JAMES F. COLBY.
